UNITED STATES PATENT OFFICE

2,610,450

APPARATUS FOR FINISHING CYLINDRICAL ARTICLES

Fred L. White, Chicago, Ill., assignor to Crane Packing Company, Chicago, Ill., a corporation of Illinois

Application March 8, 1950, Serial No. 148,455

4 Claims. (Cl. 51—129)

1

This invention relates to an apparatus for finishing cylindrical articles. For purposes of illustration, this invention will be described with reference to its application to lapping a cylindrical surface by means of a flat rotating platen. It is known that in order to secure an abrading effect upon a cylindrical surface there must be relative movement between that surface and the surface carrying the abradant. Where the latter is a disc, a rolling action instead of an abrading action will be secured between the cylindrical surface and the surface of the disc if the cylindrical surface is disposed with its axis coinciding with the radius of the disc. Under these conditions, there will be some relative movement between the two inasmuch as the linear velocity of different portions of the surface of the disc will vary in proportion to the radial position of such portions, whereas the linear velocity of all parts of the cylindrical surface will be the same.

It has been proposed to form an abrading disc for a lapping machine or the like with radial slots for carrying away excess lapping compound as well as the cuttings removed by the lapping operation. With such a surface, a radial disposition of the axis of the cylindrical article would result in a periodic longitudinal cutting of the cylindrical surface by the edges of the slots, which, of course, is not desirable from the standpoint of the formation of grooves in the cylindrical surface.

The principal object of this invention is to provide an apparatus for finishing cylindrical surfaces wherein the above-mentioned difficulties are obviated and a perfectly smooth and regular cylindrical surface is obtained.

It has also been found that should an effective relative rotation be obtained between a cylindrical surface and the surface of the disc-shaped platen, the abrading effect will be greatest at the radially outward portion of the cylindrical surface, and that should the finishing operation continue for any length of time, a tapered surface will result.

It is accordingly another object of this invention to provide an apparatus for producing a true cylindrical surface on a cylindrical object which is being abraded by a disc-shaped platen, regardless of the duration of the finishing operation.

These and other objects of this invention will become apparent from the following detailed description when taken together with the accompanying drawings, in which

Fig. 1 is a fragmentary vertical section taken through a machine which incorporates a flat ro-

2

tatable platen for finishing a cylindrical surface;

Fig. 2 is a plan view of a portion of the apparatus of Fig. 1;

Fig. 3 is a plan view of the platen used to abrade the cylindrical surface, together with a diagrammatic showing of the disposition of the cylindrical surface on the platen at different times in the cycle of the finishing operation; and

Fig. 4 is a view of the cylinder showing the effect of the abrading operation on the cylinder.

Referring now to the drawings for a detailed description of the invention and particularly to Fig. 1, there is shown a frame 10 of an article finishing machine such as a lapping machine, said frame having fixed thereto a bracket 11 having a cross bar 12 extending partially over frame 10. Rotatably mounted with respect to frame 10 is a disc-shaped platen 13 having an annular work surface 14 (Fig. 3) which is perfectly flat and smooth. Said surface 14 is interrupted by means of a plurality of radially disposed slots 15, the function of which is to receive excess abrading compound as well as the waste material produced as a result of the finishing operation. The slots 15 are substantially continuous across the usable surface of platen 13 to enable the operator to insert a cleaning tool therein. Suitable means (not shown) may be provided for rotating platen 13 at a predetermined speed during the finishing operation.

Cross bar 12 is provided with an opening 17 through which extends a pin 18 with a slip fit to enable the pin to slide to and from the platen. Said pin 18 terminates at its upper end in a knob 19, and is provided near its lower end with a collar 20, which is secured by a pin 21 to pin 18. Between collar 20 and cross bar 12 is compressed a spring 22, the function of which is to urge pin 18 downwardly toward platen 13. Intermediate cross bar 12 and knob 19 is a bar 23 which is pinned at 24 to pin 18 and is notched at its free end 25 (Fig. 2) to receive a locking pin 26 secured to cross bar 12. A second locking pin 27 located 180° away from pin 26 is fixed to cross 12 and is likewise adapted to receive the slotted end of bar 23. It is contemplated that pin 18 may be raised against the action of spring 22 by means of knob 19 until notch 25 clears pin 26, and then turned through 180° until notch 25 is aligned with pin 27, whereupon pin 18 may be allowed to return to its lowered position and thus become locked again to bar 12, but at 180° from its previous position.

The cylinder to be finished is shown at 28, and for purposes of illustration is shown as a

solid cylindrical member having center holes 29 and 30 formed at its ends. A yoke 31 is secured to the lower end 32 of pin 18 with a limited universal movement, said universal movement being secured by the use of a hinge pin 33 loosely mounted in the end 32 of pin 18, said yoke 31 having an opening 34 which is larger than the end 32 of pin 18 so as to provide ample clearance therebetween. The limited universal movement is necessary to permit the yoke to adjust itself to any undulations which might be produced by a slightly off-center mounting of platen 13 on its drive shaft.

Yoke 31 has a center pin 35 which fits into center hole 29 in cylinder 28, and a second center pin 36 which fits into the opposite center hole 30 of said cylinder. Pin 36 is axially slideable relative to yoke 31 and is provided with a knob 37 by which it may be operated. A collar 38 and a spring 39 compressed between yoke 31 and collar 38 serve to hold pin 36 in the center hole 30. Cylinder 28 is thus held in yoke 31 by center pins 35 and 36, said pin 35 being fixed in yoke 31 and center pin 36 being axially movable so as to permit a sufficient separation of the center pins 35 and 36 to allow the removal of the cylindrical article 28 from the yoke 31 and the loading of another cylinder into the yoke. The axial movement of pin 36 is effected by the operator holding the knob 37 away from yoke 31.

Referring now to Figs. 3 and 4, it will be observed that the cylinder 28 is shown in two positions both of which are disposed at angles to radii passing through the axis of the cylinder. It will be noted specifically that the radial slots 15 do not coincide with the axis of the cylinder 28 but cross it at all points. Since the axis is parallel to the elements of the cylindrical surface, it follows that the elements of the cylindrical surface will not be aligned with the slots. It will be apparent therefore that the creation of sharp, axially disposed lines in the surface of the cylinder is eliminated by the angular disposition of the cylinder and that the slots in effect sweep across the cylindrical surface as the latter is being abraded.

The mode of operating the apparatus for obtaining a true cylindrical surface on an article irrespective of the length of time that the article is being abraded by a disc-type abrading wheel, comprises the following steps:

The cylindrical article is first mounted in yoke 31 and the yoke is then disposed relative to platen 13 substantially as shown at 28 of Fig. 3 with end A of the axis of the cylinder nearest the center of the platen 13. This position is obtained by pulling upward on knob 19 against the action of spring 22 until notch 25 in bar 23 is aligned with pin 26 so as to embrace said pin. The knob is then lowered to receive pin 26 in notch 25, thereby fixing pin 18 at a predetermined angle with respect to the platen and also holding it against rotation about its own axis. The article is then run for a short test period sufficient to determine the rate of removal of stock for a given speed of rotation of platen 13 and a predetermined quality and quantity of abrading compound. From this test period, there is calculated the total time required to remove the stock to produce the desired diameter of the cylinder. This total time is then divided in half and the cylinder is abraded by the platen 13 for one-half the total time. During the abrading operation, spring 22 will maintain a predetermined pressure between the cylinder 28

and lap 13 and the cylindrical surface may become a tapered surface by the removal of stock α as shown in Fig. 4. After the lapse of said half period, cylinder 28 is lifted from platen 13 by knob 19 until bar 23 is free of pin 26, whereupon pin 18 is rotated substantially 180° until notch 25 is aligned with pin 27. Pin 18 is then lowered until pin 27 is received in said notch 25. This reverses the position of the axis of the cylindrical article so that end B thereof is now nearest the center of platen 13. Spring 22 will again maintain the same pressure between cylindrical article 28 and platen 13 and the article is abraded for the remaining one-half period in this position. During the latter one-half period, the stock shown at β in Fig. 4 will be removed and since equal periods of time are used, equal quantities of stock will be removed, thereby restoring the surface to its original cylindrical form. Thus, whenever a conical or taper effect is produced by the operation of the platen 13 upon a cylindrical article in the first position, it is completely compensated for by reversing the position of the cylindrical article and the net result is that a true cylindrical surface is obtained substantially as desired, both as to quality of finish and quantity of stock removed.

The angle between the cylinder axis and the radius intersecting the axis may vary in accordance with the cutting speed desired. The smaller the angle, the slower the stock removal and conversely, the greater the angle the faster the stock removal. If the angle is too small, however, trouble will be encountered with the slots in the platen, and if the angle is too large, the cylinder will fail to turn, thus causing a flat spot on the cylindrical surface. An angle of from 25° to 35° has been found to be satisfactory.

It is understood that the foregoing description is merely illustrative of a preferred embodiment of the invention and that the scope of the invention therefore is not to be limited thereto but is to be determined by the appended claims.

What is claimed is:

1. Apparatus for finishing cylindrical surfaces by abrasion, said apparatus comprising a rotatable platen having an abrasive flat annular surface, a frame on which the platen is rotatably mounted, and means on said frame for supporting on said annular surface an article having a cylindrical surface, with the said cylindrical surface contacting the annular surface, said means comprising a yoke, pivot means on the yoke for supporting the article for rotation about the axis of the cylindrical surface, a pin, means mounting the yoke on the pin with a limited universal movement, and means on the supporting means for supporting the pin above the annular surface to locate the article on the annular surface.

2. Apparatus as described in claim 1, a fixed bar extending over the annular surface, said bar having an opening therein and said pin being axially slidably supported in said opening, and means connected to the pin and to said bar for holding said pin against turning about the axis of said pin.

3. Apparatus as described in claim 1, a fixed bar extending over the annular surface, said bar having an opening therein and said pin being axially slidably supported in said opening, a bar fixed to the pin, and means locking the pin bar to the fixed bar in either one of two positions.

4. Apparatus as described in claim 1, a fixed bar extending over the annular surface, said bar having an opening therein and said pin being

5

axially slidably supported in said opening, a bar fixed to the pin and having a notched end, and a pair of pins on the fixed bar, one on each side of the opening, said last-mentioned pins being located to be received within the said notch, thereby holding the pin bar in either one of two positions relative to the fixed bar.
